United States Patent Office

Des. 197,629
Patented Mar. 3, 1964

197,629

DOLL PACKAGE

Amram Haddad, 43—12 50th St., New York, N.Y.

Filed Sept. 20, 1963, Ser. No. 76,654

Term of patent 14 years

(Cl. D58—2)

FIG. 1

FIG. 2

FIG. 4

FIG. 1 is a front elevational view of a doll package, showing my new design. The broken line showing of the doll in FIGURE 1 is for illustrative purposes only.

FIG. 2 is a side elevational view thereof.

FIG. 3 is a bottom plan view thereof.

FIG. 4 is a top plan view thereof.

I claim:

The ornamental design for a doll package, as shown and described.
